SEAM PRESSING MACHINE

Milton H. Roske, Malden, Mass., assignor to
United Shoe Machinery Corporation, Flemington, N. J., a corporation of New Jersey

Application July 13, 1944, Serial No. 544,728

4 Claims. (Cl. 69—7)

1

This invention relates to machines for pressing seams formed in shoe parts, for example, the back-seams of shoe uppers. These seams result from the stitching together of the marginal portions of the quarters of the shoe upper. The stitching operation is performed with the outer surfaces of the margins of the upper material in face-to-face relation, and when the quarters are turned right side out the seam presents an undesirable inwardly extending ridge. It is customary in the manufacture of shoes to employ various devices to flatten this ridge.

It is an object of the present invention to provide a seam pressing machine capable of flattening seam ridges neatly and evenly. In accordance with this object, a feature of the invention resides in the provision of a seam pressing roll of relatively large diameter and a pair of driven feed rolls positioned at opposite sides of a work support and closely adjacent to the locality of operation of the pressing roll, the feed rolls being supported in such a manner as to leave a space between them to accommodate the large diameter pressing roll. These feed rolls serve not only to control the feed of the work piece, but they also tension the work piece between them in a direction transverse to the seam. Such tensioning gives a better appearance to the finished work.

In my divisional application, Serial No. 618,004, filed on September 22, 1945, I have disclosed and claimed a method of pressing a seam, which method includes the step of tensioning the work piece transversely of the seam.

The various features of the invention including certain details of construction and combinations of parts will be described in connection with an illustrative machine and pointed out in the appended claims.

Referring now to the accompanying drawings, Fig. 1 is a front view of an illustrative machine embodying the invention;

Fig. 2 is a side view of the machine;

Fig. 3 is a large scale side elevation of the work-engaging instrumentalities;

Fig. 4 is a view in front elevation of the parts shown in Fig. 3; and

Fig. 5 is a sectional view taken on the line V—V of Fig. 3.

The operating instrumentalities of the illustrated machine comprise a driven seam pressing or seam rubbing roll 10 of relatively large diameter, a work support 12, and a pair of driven feed rolls 14 and 16. The work is guided to the operating members by a seam crease guide 18 and a seam

2

ridge guide 20. The supporting structure of the machine consists of a base plate 22 adapted to be secured to a work bench 23 (Fig. 1). The driven members and the seam ridge guide are supported by a post 24 (Fig. 2) extending upwardly from the rear of the base plate 22 and the work support comprises work-engaging members carried by a bracket 26 which is secured upon the forward portion of the base plate.

The seam pressing roll 10 is a relatively narrow disk-like member having a fluted periphery. It is secured upon a shaft 28 journaled in suitable bearings 29 carried by a pair of forwardly extending arms 30 rigidly secured to the post 24. A pulley 32 (Fig. 1) on the shaft 28 is driven by a belt 34 passing over a pulley 36. A motor 38 drives the pulley 36 directly through a shaft 40. The roll 10 is thus driven at relatively high speed.

The feed roll 14 is mounted upon the lower end of an inclined shaft 42 which is journaled and longitudinally slidable in a bearing 44 carried by the forward end of an arm 46. The bearing 44 has a cylindrical projection 33 extending through an ear on a block 35. A nut 37 threaded on the projection 33 clamps the bearing 44 in any desired position of rotary adjustment about the axis of the projection 33. The block 35 has a cylindrical shank 39 which fits in a bore in the end of the arm 46 and which is clamped in any

desired position of longitudinal and also rotary adjustment by a setscrew 31. A compression spring 43 surrounding the shaft 42 and interposed between the upper face of the feed roll 14 and a washer 45 urges the shaft 42 down. The washer 45 is held against upward movement by engagement with the lower end of a bushing 41 in the bearing 44. The downward position of the roll 14 is adjustably limited by the engagement with the upper end of the bushing 41 of a collar 47 secured by a setscrew to the shaft 42.

The rear end of the arm 46 is pivotally mounted for heightwise movement upon a pin 48 secured in the post 24. Adjustment of the heightwise position of the roll 14 is obtained by a pair of abutment screws 50 and 51 engaging the under and the upper surfaces of the arm 46 to clamp the arm at the desired level. The screw 50 is threaded through one of the arms 30 and has its upper end in supporting engagement with the arm 46,

and the screw 51 is threaded through a bracket 53 secured between the arms 30 and has its lower end bearing against the arm 46. Secured upon the upper end of the shaft 42 is a gear 52 which meshes with a worm 54 upon a shaft 56. A bracket 58 secured upon the arms 30 supports a bracket

et 60 which, in turn, carries bearings 62 and 64 in which the shaft 56 is journaled. Secured upon the rear end of the shaft 56 is a bevel gear 66 which meshes with a bevel gear 68 on a shaft 70. A pulley 72 on the shaft 70 is driven by a belt 74 which, in turn, is driven by a pulley 76 on the motor shaft 40.

The feed roll 16 is secured upon the lower end of an inclined shaft 78 journalled and longitudinally slidale in a bearing 80 which, in turn, is carried upon the forward end of an arm 82 (Fig. 1) similar to the arm 46. The bearing 80 has provisions similar to those of the bearing 44 for longitudinal and rotary adjustment. The roll 16 is yieldingly held down to a stop position by a spring 83 similar to the spring 43. The rear end of the arm 82 is fulcrumed for heightwise swinging movement upon the pin 48 and the heightwise position of the roll 16 is determined by adjusting screws 84 (Fig. 2) and 85 (Fig. 1) in the same way as the heightwise position of the roll 14 is determined by the screws 50 and 51. The drive of the roll 16 is obtained through a gear 86 secured upon the upper end of the shaft 78 and meshing with the worm 54. The rolls 14 and 16 are similar to each other and are positioned on opposite sides of the pressing roll 10, the shafts 42 and 78 being downwardly inclined toward each other. The work-engaging portions of the rolls 14 and 16 consist of rubber pads 88 set into cup-shaped ends of metal holders. The pads 88 have flat end faces which are presented to the work. These rolls are both driven at the same speed, which is materially less than the speed of the pressing roll 10. The direction of rotation of the various members is indicated by arrows on the drawings.

The work support comprises a resiliently supported roll 89 having a cylindrical periphery 90 (Fig. 5), which urges the work with yielding pressure against the rubbing roll 10. The axis of the roll 89 is positioned rearwardly (in the machine) of the common plane of the axes of the feed rolls 14 and 16. The opposite end faces of the roll 89 have conically beveled marginal portions 92 and 94. The roll 89 is carried by a shaft 96 which is journaled in a pair of spaced ears 98 mounted upon a plunger 100.

The plunger 100 is movable heightwise in a guideway formed in the bracket 26 and is urged upwardly by a spring 104 (Fig. 2) housed in a bore in the plunger. It is kept from turning by a screw pin 101 (Fig. 2) entering a groove 103 in the plunger. The lower end of the spring 104 bears against the upper end of an adjusting screw 106 threaded into the bracket 26 and having a knurled head 108 by which it can be turned to adjust the compression of the spring 104. Upward movement of the work support under the influence of the spring 104 is limited by a stop 128 (Fig. 2) having its upper end hooked over a projection extending from the base of the ears 98. The stop 128 is clamped to the bracket 26 by a screw 130 threaded into the bracket and passing through a slot formed in the stop to permit heightwise adjustment. Fine adjustment of the stop 128 is facilitated by a screw 132 threaded into a lug 134 extending from the bracket 26. The screw 132 passes loosely through a lug 136 on the stop 128 and has a head which bears against the lug 136. The bracket 26 is secured to the base plate 22 by clamping screws 110 which extend through suitable slots in the bracket to provide for forward and rearward adjustment of the bracket. Such adjustment is

desirable in assembling the machine in order to provide for bringing the work support into proper relation to the seam pressing roll 10.

The seam crease guide 18 consists of an upstanding blade-like member curved about part of the roll 89 and extending close to the locality of operation. The lower end of the crease guide 18 is carried by a bracket 112 which is secured to the ears 98.

The seam ridge guide 20 (Figs. 2, 3 and 4) consists of an inverted channel or U-shaped member extending close to the locality of operation. The upper part of the guide 20 is straight and is guided for heightwise movement in a guideway 114 which is carried upon the end of a rod 116 extending forwardly from the bracket 60. The guideway 114 is clamped to the rod 116 by screws 118. This arrangement for securing the guideway 114 permits it to be properly positioned during assembly by sliding the guideway forwardly or rearwardly along the rod 116 and by turning it about the axis of the rod. The seam ridge guide 20 is yieldingly urged down to a stop position by a tension spring 120 having its lower end secured to a pin 122 extending from the guideway 114. The upper end of the spring 120 is secured to a pin 124 on the seam ridge guide 20. Downward movement of the guide 20 is stopped by engagement of the upper end of a slot 160 in the guide 20 with a conical end of a screw 162 threaded into the wall of the guideway 114 and having a knurled head.

In the operation of the machine a work piece W having a seam ridge R is fed by hand, in inside-out position, with the seam ridge entering the guide 20 and the seam crease lying over the guide 18. The feed rolls 14 and 16, under the yielding pressure of their springs 43, engage the leading edges of the work and press the work against the bevels 92 and 94, respectively. The feed rolls thus grip the work piece and advance it until the leading edge of the work piece is engaged by the pressing roll. The effect of the feed rolls thereafter is to control the feed of the work piece by holding it back against the tendency of the rapidly rotating pressing roll to eject it from the machine. The feed rolls 14 and 16 have another important function; they tension the work transversely of the seam. Since the axis of each of the feed rolls passes, not through the axis of the work support, but in advance of the axis of the work support (with respect to the direction of feed), the portion of each feed roll which grips the work will be moving in a direction having a component away from the seam as well as a component of feed control in the direction of the seam. The components away from the seam will cause each roll to exert a wiping action upon the work piece in opposition to the other roll, and will thus result in a tensioning of the work piece between the two feed rolls. Such tensioning improves the appearance of the finished work.

The work piece W, thus fed under transverse tension to the rubbing roll 10, is pressed against the rubbing roll by the spring 104 operating through the roll 89. The relatively large diameter of the rubbing roll 10 (rendered possible by the novel arrangement of the feed rolls) enables high peripheral speeds of the rubbing roll to be attained, with a corresponding reduction in the pressure necessary to flatten the seam. Such use of high peripheral speed of the rubbing roll with relatively light pressure on the seam avoids straining the stitches and contributes to the improved appearance of the finished work.

Having described my invention, what I claim as new and desired to secure by Letters Patent of the United States is:

1. In a seam pressing machine, a support for a work piece having a seam ridge, a pair of members having work-engaging surfaces adapted to contact a work piece on said support on opposite sides of the seam ridge, means for mounting said members for movement in which the work-engaging portions of said members wipe the work piece in directions away from the seam ridge to tension the work piece across the seam ridge, and means for driving said members to effect such wiping action.

2. In a seam pressing machine, a work support, means for guiding a work piece having a seam ridge for movement in the direction of said seam ridge, and a pair of driven rolls arranged to grip the work piece against the work support on opposite sides of the seam ridge, said rolls being arranged to cause the rotational movement of their work-gripping portions to be away from the seam to create a transverse tension in the work piece.

3. A seam pressing machine comprising a seam pressing roll of relatively large diameter, a work support, a pair of driven feed rolls at opposite sides of the work support closely adjacent to the locality of operation of the pressing roll, and

supporting means for the feed rolls constructed and arranged to leave a space between the feed rolls to accommodate the large diameter pressing roll.

- 5 4. A seam pressing machine comprising a seam rubbing roll of relatively large diameter, a member below said seam rubbing roll for supporting the seam of a work piece against the pressure of the seam rubbing roll, a pair of driven shafts 10 at opposite sides respectively of the seam rubbing roll, said shafts converging downwardly, and a feed roll on the lower portion of each of said shafts, said feed rolls having work-engaging portions of rubber and co-operating with said seam-supporting member to control the feed of the work.

MILTON H. ROSKE.
